CLAIM

The ornamental design for a display screen with graphical user interface, as shown and described.

DESCRIPTION

FIG. 1 is a drawing showing a display screen with graphical user interface for a display screen, in accordance with a first embodiment of the invention;

FIG. 2 is a drawing showing a display screen with graphical user interface for a display screen, in accordance with a second embodiment of the invention;

FIG. 3 is a drawing showing a display screen with graphical user interface for a display screen, in accordance with a third embodiment of the invention;

FIG. 4 is a drawing showing a display screen with graphical user interface for a display screen, in accordance with a fourth embodiment of the invention;

FIG. 5 is a drawing showing a display screen with graphical user interface for a display screen, in accordance with a fifth embodiment of the invention;

FIG. 6 is a drawing showing a display screen with graphical user interface for a display screen, in accordance with a sixth embodiment of the invention;

FIG. 7 is a drawing showing a display screen with graphical user interface for a display screen, in accordance with a seventh embodiment of the invention; and,

FIG. 8 is a drawing showing a display screen with graphical user interface for a display screen, in accordance with a eighth embodiment of the invention.

The broken lines showing a display screen and elements of the graphical user interface illustrate portions of the article, and form no part of the claimed design.
